UNITED STATES PATENT OFFICE.

NELLIE M. SPRINGHORN, OF BLUE POINT, NEW YORK.

STOVE-POLISHING MITTEN.

1,046,230.

Specification of Letters Patent. Patented Dec. 3, 1912.

Application filed April 17, 1912. Serial No. 691,321.

To all whom it may concern:

Be it known that I, NELLIE MAY SPRINGHORN, a citizen of the United States, and a resident of Blue Point, in the county of 5 Suffolk and State of New York, have invented a new and Improved Stove-Polishing Mitten, of which the following is a full, clear, and exact description.

The object of the invention is to provide 10 a new and improved stove polishing mitten, designed to enable the user to keep a blackened stove in fine polish without requiring re-blackening for some time, and to readily remove water, grease spots and other extraneous matter, thus keeping the stove 15 clean and nice for a long time and without danger of rusting. For the purpose mentioned, use is made of a rubber mitten, a bag held detachably on the inner face of the 20 said mitten and filled with a dry polishing powder, and removable superimposed rubbing pieces of cloth following the shape of the said bag, the latter and the said rubbing pieces being of a comparatively loosely 25 woven fabric material to permit the dry powder in the bag to work through the meshes of the fabric to the outermost rubbing piece to be rubbed onto the stove surface when using the mitten for polishing 30 purposes.

A practical embodiment of the invention is represented in the accompanying drawings forming a part of this specification, in which similar characters of reference indicate 35 corresponding parts in both views.

Figure 1 is a face view of the stove polishing mitten with portions of the rubbing pieces folded back and part of the bag broken out; and Fig. 2 is a sectional side 40 elevation of the same.

The stove polishing mitten consists essentially of a mitten A, preferably made of rubber or a similar material impervious to a dry powder, a bag B containing the dry 45 polishing powder C and a series of rubbing pieces D, D', D² superimposed one upon the other and following the bag B, which in turn is arranged on the inner face of the mitten A. The bag B and the rubbing pieces D, D', D² are made of a fabric material woven sufficiently loose to permit the powder C to gradually work through the meshes of the fabric material until it reaches the outer face of the outermost rubbing piece D² so that the powder can be 50 rubbed over the surface of the stove with a

view to polish the same and to remove water, grease spots and other extraneous matter. The bag B as well as the rubbing pieces D, D', D² follow the shape of the mitten A 60 at the sides and forward end thereof, the mitten being preferably provided with thumbs on opposite sides to permit of using the mitten on either hand.

The bag B and the rubbing pieces D, D', D² are preferably removably fastened in position on the mitten A and for this purpose use is made of a lacing E passing through registering eyelets F arranged along the sides and forward margin of the 70 mitten A, the bag B and the rubbing pieces D, D', D².

By the arrangement described the outermost rubbing piece D², in case of being worn, may be readily removed so as to permit using the next following rubbing piece as the one coming in contact with the stove 75 surface, or the outermost rubbing piece if burned out can be replaced by a new one, it being understood that by the use of a 80 number of superimposed rubbing pieces the passage of the powder from the bag to the outermost surface is retarded to prevent too much of the powder from working through to the outer surface of the outermost layer. 85

The bag B is normally closed at the wrist end by sewing, which can be readily opened to permit of refilling the bag with a new quantity of the powder whenever it is 90 deemed necessary.

An insulating material G, such as asbestos in sheet or loose form, is preferably interposed between the bag B and the mitten A so as to protect the hand and the rubber mitten from the heat incident to using 95 the stove polishing mitten on a hot stove.

From the foregoing it will be seen that by the arrangement described a stove after being blackened in the usual manner can be readily polished by the user rubbing the mitten with the outer face of the outermost rubbing piece D² in contact with the stove. It is further understood that by using a mitten A of rubber the hand is protected 100 against being soiled by the polishing powder C and the hand is also protected from the heat of the stove by the interposed insulating material G. 105

Having thus described my invention, I claim as new and desire to secure by Letters 110 Patent:

1. A stove polishing mitten, comprising a

mittens impervious to polish powder, a bag filled with a polishing powder and overlying the inner face of the mitten, a rubbing piece overlying the outer face of the said bag, and means for detachably fastening the said bag and rubbing piece to the said mitten, the said bag and rubbing piece being made of a fabric material woven sufficiently loosely to permit the powder in the bag to work through to the outer face of the rubbing piece.

2. A stove polishing mitten, comprising a mitten impervious to polish powder, a bag filled with a polishing powder and overlying the inner face of the mitten, a rubbing piece overlying the outer face of the said bag, the

said bag and rubbing piece following the shape of the said mitten and being made of a loosely woven fabric material to permit the powder in the bag to work through to the 20 face of the rubbing piece, and a lacing engaging the outer margins of the mitten, bag and rubbing piece to detachably fasten the said parts together.

In testimony whereof I have signed my 25 name to this specification in the presence of two subscribing witnesses.

NELLIE M. SPRINGHORN.
